US00D755053S

(12) **United States Design Patent**
Davis et al.

(10) **Patent No.:** **US D755,053 S**
(45) **Date of Patent:** **** May 3, 2016**

(54) **CONTAINER**

(71) Applicant: **Robinsons Soft Drinks Limited**, Hemel Hempstead (GB)

(72) Inventors: **William John Davis**, Bath (GB); **David James McNeill**, Bath (GB)

(73) Assignee: **Robinsons Soft Drinks Limited**, Hemel Hempstead (GB)

(**) Term: **15 Years**

(21) Appl. No.: **29/527,478**

(22) Filed: **May 19, 2015**

Related U.S. Application Data

(63) Continuation of application No. 29/471,690, filed on Nov. 4, 2013, now Pat. No. Des. 741,182.

(30) **Foreign Application Priority Data**

Aug. 8, 2013 (EM) 002288936

(57) **CLAIM**

The ornamental design for container, as shown and described.

DESCRIPTION

FIG. 1 is a perspective view of a container showing our new design.

FIG. 2 is a front elevation view of the container of FIG. 1.

FIG. 3 is a back elevation view of the container of FIG. 1.

FIG. 4 is a left side elevation view of the container of FIG. 1; and,

FIG. 5 is a right side elevation view of the container of FIG. 1.

FIG. 6 is a top plan view of the container of FIG. 1; and,

FIG. 7 is a bottom plan view of the container of FIG. 1.

The portions of the drawings shown in broken lines represent environmental structure and form no part of the claimed design.

1 Claim, 5 Drawing Sheets
